ADJUSTABLE DISCHARGE LOUVER DEVICE
FOR AIR CONDITIONERS

William S. Stair, York, Pa., assignor to York Corporation, York, Pa., a corporation of Delaware

Application December 8, 1950, Serial No. 199,834

6 Claims. (Cl. 98—40)

1

This invention relates to discharge louvers for units such as air conditioners, room coolers and the like.

The requirements are conflicting. Quiet operation is indispensable. Compactness of the conditioner unit is so important that space occupied by the fan and the discharge plenum must be held to the practicable minimum. Yet the discharging conditioned air should flow with sufficient velocity to assure good distribution. These requirements present a substantial problem even if the direction of discharge be fixed.

The invention provides an adjustable louver mechanism which affords two components of angular adjustment, each independent of the other, and each of substantial range. One component adjustment can be made without increasing the throttling effect of the louvers as the angle increases. As to the other component, the increase in throttling is not significant until the limit of adjustment is closely approached.

It is characteristic of the improved construction that the louvers are short, and in terms of proportion rather massive, so that when molded in materials of comparatively low specific weight, resonance is minimized. The adjustable frame in which the louvers are mounted, though long, is not so slender in cross section as to respond resonantly to the flowing air. Moreover, it is muffled to an extent by the louvers. In fact the whole assembly is distinctly non-resonant, partly because it is formed almost exclusively of molded plastic material, but in greater degree because of form and proportion.

Two embodiments of the invention will now be described by reference to the accompanying drawings, in which:

Fig. 1 is a perspective view of the improved louver structure, mounted in an inclined surface at the upper front margin of the case of a conditioner of the window-sill-mounted type.

Figs. 2, 3 and 4 are respectively face elevation, back elevation and end elevation of the frame or mount which supports the improved louver structure.

Fig. 5 is a side elevation of the swiveled secondary louver-carrying frame, as it appears removed from the mount shown in Figs. 2-4, with the louvers in place.

Fig. 6 is a section on the line 6—6 of Fig. 1, drawn on a larger scale than any of Figs. 1-5.

Fig. 7 is a similar section on the line 7—7 of Fig. 1. The plane of section is more precisely indicated by the line 7—7 of Fig. 9.

Fig. 8 is an end elevation of the swiveled sec-

2

ondary frame of Fig. 5, drawn on the scale of Figs. 6 and 7. The louvers are shown in broken lines.

Fig. 9 is a fragmentary section on the line 9—9 of Fig. 8.

Fig. 10 is a perspective view of one of the two retainer straps used to hold the swiveled frame of Fig. 5 in assembled relation with the mount of Figs. 2-4.

10 Figs. 11 and 12 are views of a modified dual louver construction in which two swiveled frames each with louvers are arranged side by side in a duplex mount, Fig. 11 being a section on the line 11—11 of Fig. 12 and Fig. 12 is a section on the line 12—12 of Fig. 11.

In Figs. 1 and 6 the decorative casing of a conditioner has a front wall 15, an end wall 16 and a top 17.

20 A frame generally indicated in Fig. 1 by the numeral 18 is mounted in an apertured inclined portion 19 of the casing which forms the junction between front 15 and top 17. As indicated in Fig. 6 the frame 18 conforms to the margin of the aperture, which aperture obviously is the discharge port for conditioned air.

25 Refer now also to Figs. 2-5. In addition to the side members 21, the frame 18 has decorative faceted end portions 22 and adjacent to these has arched portions 23, which, as viewed from the bottom (Fig. 3), are internally formed as cylindrical half bearings 24, each with a groove 25. The holes 26 are to receive threaded fastenings (not shown) used to attach the frame to the casing. The threaded holes 27 are to receive screws 28 (see Fig. 7) used to attach arcuate straps 29 (see Fig. 10) which complete the bearings 24. These straps are of metal and can be so formed as to develop a desired degree of friction on the swiveled outlet frame 31.

30 35 40 45 The frame 31 is shown in detail in Figs. 5 to 9 inclusive. It is rotatably supported on two journals 32, and in the illustrated embodiment these are at the extreme ends of the frame. On each journal is a rib 33 designed to work freely in a corresponding groove 25 in the corresponding bearing in frame 18. As best indicated in Fig. 7, the arcuate extent of the grooves is 180°. That of the ribs is less, to the extent necessary to permit the desired rotary movement. As indicated in Figs. 6 and 7 the two attaching flanges of strap 29 serve as stops and are engaged by the ends of the rib.

40 45 Between the journals 32 the member 31 is longitudinally slotted and thus consists of two bars 34 which are segments of a circle in cross sec-

tion. In the example illustrated the diameter of this circle is equal to the diameter of the journals 32 and the width of the slot is approximately $\frac{3}{4}$ of the diameter. The slot is substantially continuous from journal to journal, since it is interrupted by one bridge piece 35 which carries a finger piece 36 by which the frame may be adjusted. The frame is split longitudinally (see Figs. 5, 7 and 8) and the two halves are connected by screws 37.

The opposed inner faces of the segmental bars 34 have each a row of shallow cylindrical cavities 38 which serve as bearings for disc-like trunnions 39 formed at each end of louvers 41 which extend across the slot in frame 34. The bearing cavities and the trunnions which turn in them are of a diameter which is several times their axial dimension. Each trunnion is cut away at one side, along the secant plane 42, and a friction-developing spring 43 is inserted in each of the spaces so afforded.

With the construction illustrated and above described, adjustment of frame 34 varies the direction of air discharge through a vertical angle of about 45° . Even the extreme adjustments do not impose any increased throttling effect. Individual louvers may be set in different angular positions through a range of 90° , i. e. about 45° in opposite directions from the positions shown in Fig. 9. In extreme adjustments the louvers will throttle flow.

The invention thus provides a louver construction which affords good directional control of discharge flow, and presents a notably attractive appearance. It occupies very little space, is easily manipulated and does not resonate.

While the angle mounting shown in Figs. 1-10 presents advantages, the construction is adaptable to mounting in a front, side or top wall of a cabinet. Figs. 11 and 12 show an arrangement worked out for top-wall mounting in a conditioner of remarkably small over-all dimensions.

In Figs. 11 and 12 the front wall of the conditioner is shown at 115 and the top at 117. The outlet opening is surrounded by rubber-like gasket 116. The analogue of frame 18 is shown at 118. It fits within gasket 116 and has a flange which seats on top 117, and a bridge piece 121 which adapts it to receive two swiveled frames 131. These turn on trunnions 132 which in this embodiment are relatively small. The frames 131 are slotted from end to end. They are individually manipulable by finger pieces 133. The louvers 141 and their trunnions 139 are similar to those shown in the first embodiment.

Obviously, the frame 118 must be made in two parts to permit assembly of the frame 131 with it. The plane of separation is not indicated but should be parallel with the plane of the paper in Fig. 11. To permit mounting of the louvers, the frames 131 must be split, but this detail does not require illustration. To simplify the drawing, friction springs such as the springs 43 of Fig. 9 are not illustrated, but their use with any or all of the trunnions is obviously possible.

I claim:

1. In a flow directing device the combination of an elongated generally cylindrical member having coaxial cylindrical journals and a longitudinal slot extending approximately throughout the length of the member, the side walls of said slot each having a series of bearings, the bearings of the two series being axially aligned in pairs; a plurality of louvers whose length ap-

proximates the width of said slot, said louvers having trunnions at their opposite ends which trunnions are confined in corresponding pairs of said bearings; and a supporting frame having an opening shaped to receive and freely fit said cylindrical member and having bearings in which respective journals are rotatable.

2. In a flow directing device the combination of an elongated generally cylindrical member having coaxial cylindrical journals of diameters approximating that of the cylindrical member at opposite ends thereof, and a longitudinal slot extending substantially throughout the interval between said journals and of a width subtending a major portion of the diameter of said member, the side walls of said slot each having a series of bearings, the bearings of the two series being axially aligned in pairs; a plurality of louvers whose length approximates the width of said slot, said louvers having trunnions at their opposite ends which trunnions are confined in corresponding pairs of said bearings; and a supporting frame having an opening shaped to receive and freely fit said cylindrical member and having end bearings in which respective journals are mounted to turn.

3. In a flow directing device the combination of an elongated generally cylindrical member having coaxial cylindrical journals of diameters approximating that of the cylindrical member at opposite ends thereof, and a longitudinal slot extending substantially throughout the interval between said journals and of a width subtending a major portion of the diameter of said member, the side walls of said slot each having a series of bearings, the bearings of the two series being axially aligned in pairs; a plurality of louvers whose length approximates the width of said slot, said louvers having trunnions at their opposite ends which trunnions are confined in corresponding pairs of said bearings; a supporting frame having an opening shaped to receive and freely fit said cylindrical member and having end bearings in which respective journals are mounted to turn; and means for resisting endwise motion of said cylindrical member and limiting rotary motion thereof, comprising inter-engaging rib and groove means associated with at least one journal and the end bearing in which it turns.

4. In a flow directing device the combination of an elongated generally cylindrical member having coaxial cylindrical journals, and a longitudinal slot extending approximately throughout the length of the member, the side walls of said slot each having a series of bearings, the bearings of the two series being axially aligned in pairs; a plurality of louvers whose length approximates the width of said slot, said louvers having trunnions at their opposite ends which trunnions are materially larger in diameter than the thickness of the louvers, and are confined in corresponding pairs of said bearings; elastic friction means reacting between the various trunnions and their bearings; and a supporting frame having an opening shaped to receive and freely fit said cylindrical member and having end bearings in which respective journals are received.

5. In a flow directing device the combination of an elongated generally cylindrical member having coaxial cylindrical journals of diameters approximating that of the cylindrical member at opposite ends thereof, and a longitudinal slot extending substantially throughout the interval between said journals, the side walls of said slot

each having a series of bearings, the bearings of the two series being axially alined in pairs; a plurality of louvers whose length approximates the width of said slot, said louvers having trunnions at their opposite ends which trunnions are materially larger in diameter than the thickness of the louvers, and are confined in corresponding pairs of said bearings; elastic friction means reacting between the various trunnions and their bearings; a supporting frame having an opening shaped to receive and freely fit said cylindrical member and having end bearings in which respective journals are mounted to turn; and means for resisting endwise motion of said cylindrical member and limiting rotary motion thereof, comprising inter-engaging rib and groove means associated with at least one journal and the end bearing in which it turns.

6. In a flow directing device the combination of an elongated generally cylindrical member having coaxial cylindrical journals of substantially the same diameter as the member at its opposite ends, and a longitudinal slot extending substantially throughout the interval between said journals and of a width approximating three fourths of the diameter of said member, the side walls of said slot each having a series of bearing-forming cylindrical recesses whose diameter

greatly exceeds their depth, the recesses of the two series being axially alined in pairs; a plurality of louvers whose length approximates the width of said slot, said louvers having disc-like trunnions projecting at their opposite ends and respectively confined in corresponding recesses, said trunnions being peripherally notched; friction-developing springs in the various notches; and a supporting frame having an opening shaped to receive and freely fit said cylindrical member and having end bearings in which respective journals are confined.
